Primary Examiner—Donald P. Walsh*Assistant Examiner*—Jeffrey Asch*Attorney, Agent, or Firm*—Flynn, Thiel, Boutell & Tanis**[57] CLAIM**

The ornamental design of a covered corner workstation, as shown and described.

DESCRIPTION

FIG. 1 is a perspective view of a covered corner workstation showing our design;

FIG. 2 is a top plan view thereof;

FIG. 3 is a front elevational view taken from the left side, the front view taken from the right side being a mirror image thereof;

FIG. 4 is a rear elevational view taken from the right side, the rear view taken from the left side being a mirror image thereof; and,

FIG. 5 is a perspective view of a second embodiment of that shown in FIG. 1.

FIG. 1

FIG. 2

FIG. 3

FIG. 4

FIG. 5
